UNITED STATES PATENT OFFICE.

HARRY C. HORNISH, OF PEORIA, ILLINOIS.

STOVE OR FURNACE.

SPECIFICATION forming part of Letters Patent No. 508,474, dated November 14, 1893.

Application filed January 28, 1893. Serial No. 460,024. (No model.)

To all whom it may concern:

Be it known that I, HARRY C. HORNISH, a citizen of the United States, residing at Peoria, in the county of Peoria and State of Illinois, have invented certain new and useful Improvements in Stoves or Furnaces; and I do hereby declare the following to be a full, clear, and exact description of the invention, such as will enable others skilled in the art to which it appertains to make and use the same.

This invention relates to improvements in stoves or furnaces of that class in which gases of whatever origin or nature may be used and also in which electricity may be used and by which the electric heater may be used after removing the gas burner.

The object of the invention is to provide a stove or furnace in which a larger surface of metal is presented to the heating agent than in any other stove or furnace yet devised and thus getting a greater amount of heated air from the same amount of fuel used in any other device of this class.

In the appended drawings, Figure 1 represents a sectional elevation of the stove. Fig. 2 represents a plan view of the stove through dotted line $x x$ Fig. 1. Fig. 3 is an elevation of a portion of the lower end of the stove.

In the several figures, A represents the outer casing of the stove which is made of any suitable material and of any suitable height and diameter, and which is surmounted by a top plate B, provided with an escape pipe C. The lower portion of said casing flares outwardly at A' and forms the larger body or drum A² and this drum drops perpendicularly for some distance and is provided with the bottom A³ mounted on legs A⁴. With the bottom A³ is made a depending flange or collar D, located centrally and which is open at the bottom as shown. A gas burner E of the usual construction for such stoves is placed within this depending flange D and is held therein by resting upon one or more rods F F Figs. 1 and 2. The top of the burner E projects somewhat above the bottom A³ and a deflecting plate G forming the bottom of a hot air chamber H is located directly above said burner and is sustained in place by any suitable means. This hot air chamber is made in any convenient shape desired; the one shown however is circular in form, its inter-

rior surfaces, upper and lower, being parallel one with the other except the central portion of the bottom which drops into a depending basin and the said bottom forming the deflecting plate G is made of considerable thickness immediately over the burner and both the inner and lower surfaces of said plate are provided with a number of heavy lugs for retaining the heat. The air chamber however is not entirely closed, but has openings into which upper and lower pipes I and J are inserted in the top and bottom plates respectively of said chamber.

As shown in Figs. 1 and 2 the upper ends of the pipes J open into the bottom of the chamber H, and the lower ends of same pass through the bottom A³ of the stove, thus forming an opening from the outer air through the said bottom A³ and pipes J into the said air chamber. These pipes J are set in two continuous circular rows, each pipe of a row being equidistant from the center of the stove, and each pipe of the series of pipes of the outer row being set back of, and between the pipes of the inner row, as may be understood by reference to Fig. 2. I do not restrict myself however to two rows of pipes only but one or more rows may be employed satisfactorily.

The upper pipes I are let into the upper plate of the hot air chamber as before stated, and being the same in number as the lower pipes J, may be set immediately over the said lower pipes to form a direct unbroken passage from the pipes J to the pipes I, or the upper series of pipes I may be set around slightly to bring the pipes of each tier out of the direct line to cause more heat radiation.

The upper and lower ends of each of the vertical pipes of the stove are provided with annular flanges a a either to allow the pipe to rest upon a portion of the stove, or for the pipe to support a portion thereof. The upper ends of the pipes I support a second hot air chamber K. This chamber is circular in form and of such diameter as to fit snugly within the casing A, and the top and bottom of which are parallel as shown, and the center portion of this chamber is cut out top and bottom, but closed within itself, to form the opening K' for the passage of heat. This box or chamber then is merely a closed hollow

ring whose passages are of rectangular cross section, and having the pipes I opening into the bottom thereof, while the top of same is opened into by the pipes K² of the proper length and which support and open into a third hot air chamber L of the form of the lower chamber H with the depending basin L' except that the bottom thereof is not as heavy as the said chamber H and the chamber is smaller than the chamber K to allow of an air passage between itself and the outer casing A. Then a fourth series of pipes L² opens into this chamber at the top and support at their upper ends a fourth chamber M of the same shape and fitted the same as the chamber K and this is succeeded by the series of pipes M², the chamber N with its depending basin N', of the same size, form and location as the chamber L and this chamber N is succeeded by the pipes N² which pass through the top B. These ends of the pipes N² are flared to fit the openings in the top by fitting and driving in the wedge shaped rings or collars N³ having the projecting lips N⁴.

5 The casing A is enlarged at the bottom into the drum A² for the purpose of admitting the pipes O from the bottom A³ which is an extra series of pipes set outside of the pipes J as shown in Figs. 1 and 2, to conduct air 10 from the outside into the air chamber H. The said pipes O open into the horizontal pipes P which connect the chamber H with the outer casing of drum A². Thus it will be seen that air may be taken either from the room through 15 pipes P and regulated by an ordinary damper P' or the air may be taken in from the outside air through the air conduit Q through the pipes O. The pipes O and P may be also put in separately as desired. The said air 20 conduit Q is secured by any good means to the bottom of the stove or furnace and which incloses the entire bottom thereof and leads to the outer air and this of course furnishes pure 25 air and plenty of it to be heated. The said air conduit is provided with doors Q' through 30 which may be taken the air from the rooms to be heated. Now the burner being of a less diameter than the depending flange D, the air may easily get to the burner through the 35 passage D' thus left, and thereby giving said burner a perfect draft. The draft thus given 40 may be perfectly regulated by the following means:—A funnel R is hung from the flange D by the before mentioned rods F and the 45 neck of the funnel is elongated into the pipe S which is carried up to a damper T cast with the 50 lower portion of the stove. This damper is of ordinary form simply being a plate with the holes made therein and closed or opened 55 by a pivoted swinging plate to correspond therewith. The rods F pass through holes drilled through the funnel and the flange D and split pins are inserted in holes in either 60 ends of said rods to keep them in place, so that when it is desired to take out the burner the rods are simply withdrawn and the burner 65 can be quickly removed. An opening is made

in the flange D and a door D² is hung to admit the hand to the burner. A pipe shown by E' leads from the fuel supply to the burner. A 70 number of doors A⁵ are located around the drum A² for taking air in if desired. The lower portion of the drum portion A² is provided with a series of holes U near its bottom and a collar V (Fig. 3) (shown raised) is 75 placed over them and is provided with holes W corresponding with the holes U. The collar rests on a flange X on the bottom of the drum and is provided with a wing or a lug to assist in the operation of same. 80

For using as a furnace, an auxiliary casing is made to envelop the device described and from that casing pipes lead to different rooms to be heated.

The operation of the device is as follows:— 85 The oil, gas or whatever fuel is used may be admitted to the burner and the burner is lighted through the door D² in the flange D and the flame from the burner impinges on the deflecting plate and the plate being thus 90 heated throws its heat from the interior of the chamber H up through the pipes above and mixing with the hot air from the other chambers passes out into the room. The heat from the flame and bottom side of the deflecting plate passes outward and toward the casing A² passing and impinging upon the pipes O and P and J and thence up between the outer casing and the chamber H thence back toward the center of the stove between the 100 pipes I I and through the central opening K' in the air chamber K, thence outwardly again between the pipes K² and between the chamber L and casing A then toward the center again and up and so on to the escape pipe C. 105 As the heat from the burner passes between the series of pipes and under the series of hot air chambers the said pipes and chambers are heated to a very great extent, and by the time 110 said heated air from the burner reaches the escape pipe, it has lost its warmth in heating the pipes and chambers before mentioned.

I claim—

1. In a stove or furnace an outer circular casing A flaring at its lower extremity to form 115 a circular drum A² provided with the bottom A³ having the depending open annular flange D provided with one or more rods F for retaining a burner therein, a circular hot air chamber H of rectangular cross section centrally located within the drum A² and having the depending basin G provided with lugs on 120 its upper and lower surfaces, and the pipes J J supporting from the bottom A³ the said hot air chamber H and opening thereto forming an air passage through the bottom A³ into the said hot air chamber H substantially 125 in the manner and for the purposes herein set forth and described.

2. In a stove or furnace, an outer circular 130 casing A flaring at its lower extremity to form a circular drum A², provided with one or more rods F, the circular hot air chamber H of rectangular cross section, the pipes J resting

on the bottom A³ and opening therethrough and supporting and opening into the said chamber H, the horizontal radiating pipes P, radiating from the periphery of the said air chamber and forming an air passage from the said hot air chamber to the outer air through the drum casing A², the vertical pipes O, the lower end opening through the bottom A³ and its upper end opening into the horizontal pipe P substantially in the manner set forth and described.

3. In a stove or furnace an outer circular casing A flaring at its lower extremity to form the drum A² provided with the bottom A³ having the depending open annular flange D with one or more rods F, a circular hot air chamber of rectangular cross section centrally located within the said drum A², and having its upper and lower plates parallel with each other, the lower plate having a depending basin G formed therewith, the upper and lower surfaces of said lower plate being provided with lugs in the manner and for the purposes herein described and shown.

25 4. In a stove or furnace an outer casing A flaring at its lower extremity to form the drum A² provided with the bottom A³ having the depending open annular flange D with one or more rods F, a circular hot air chamber H, of rectangular cross section having its upper and lower plates parallel with each other, the lower plate having a depending basin G centrally located in said bottom, the pipes J supporting the said air chamber from the bottom A³ the upper pipes I opening into said hot air chamber and also opening into and supporting a second hot air chamber K with the opening K' in form of a hollow ring, the passages thereof being of rectangular cross section, said chamber K being adapted to fit snugly within the casing A in the manner and for the purposes herein set forth and described.

5. In a stove or furnace an outer circular casing A flaring at its lower extremity to form the drum A² provided with the bottom A³ having the depending open annular flange D, the hot air chamber H supported by the pipes J, the pipes I resting on the chamber H and supporting the chamber K, the pipes K² resting on the chamber K and supporting the chamber L, said chamber L having substantially the same form and position as the said chamber H, and thus continuing to build up a continuous series of chambers and pipes to form the stove; the uppermost series of pipes opening through the top plate of the stove and having a tapering collar or thimble inserted in each in the manner and for the purposes herein set forth and described.

6. In a stove or furnace an outer circular casing A flaring at its lower extremity to form

a drum A² provided with the bottom A³ having the depending open annular flange D, the hot air chamber H, supported by pipes J, said air chamber H being surmounted by a series of connecting pipes and hot air chambers every other one of said air chambers being of less diameter than the interior diameter of the casing A, and the intermediate chambers being of the full diameter of the interior of the casing and provided with openings through the centers of same each chamber of the series being connected by pipes into a continuous chain in the manner and for the purposes herein set forth and described.

7. In a stove or furnace, a series of hot air chambers and vertical conducting pipes alternately arranged, one series above another, said pipes being so placed as to form a passage from the lower to the upper portion of the series substantially in the manner and for the purposes set forth and described.

8. In a stove or furnace an outer circular casing A flaring at its lower extremity to form a drum A² provided with bottom A³ having the depending open annular flange D supporting a burner by the rods F F, a funnel R forming an air chamber encircling the said flange D and supported by the said rods F and a draft pipe S opening into said chamber and said pipe S being provided at its free end with a damper for admitting and regulating the air supply to the burner substantially in the manner and for the purposes herein set forth and described.

9. In a stove or furnace a circular hot air chamber H of rectangular cross section, mounted and supported on the vertical pipes J, said pipes resting upon and opening through the bottom A³, the upper ends of said pipes opening into the said hot air chamber, a series of vertical pipes opening into the periphery of the said chamber H and admitting air thereto through the bottom A³ of the stove for the purposes herein set forth and described.

10. In a stove or furnace, a circular hot air chamber H, of rectangular cross section mounted and supported on the vertical pipes J, said pipes resting upon and opening into the said hot air chamber, a series of horizontal conducting pipes P opening into the periphery of the said hot air chamber and radiating therefrom admitting air through the drum A² into said chamber H, the air supply being regulated by the dampers P' in the outer ends of said pipes P in the manner set forth and described.

In testimony whereof I affix my signature in presence of two witnesses.

HARRY C. HORNISH.
